UNITED STATES PATENT OFFICE.

FRANK R. MCBERTY, OF DOWNTONERS GROVE, ILLINOIS, ASSIGNOR TO THE
WESTERN ELECTRIC COMPANY, OF CHICAGO, ILLINOIS.

CALLING APPLIANCE FOR TELEPHONE-SWITCHBOARDS.

SPECIFICATION forming part of Letters Patent No. 678,369, dated July 16, 1901.

Application filed June 17, 1898. Serial No. 683,737. (No model.)

To all whom it may concern:

Be it known that I, FRANK R. MCBERTY, a citizen of the United States, residing at Downtoners Grove, in the county of Dupage and State 5 of Illinois, have invented a certain new and useful Improvement in Calling Appliances for Telephone-Switchboards, (Case No. 62,) of which the following is a full, clear, concise, and exact description.

10 This invention concerns the automatic application of a source of calling-current to a telephone-line in the act of making connection with a line, the control of the circuit to the operator's telephone involved in testing lines, and the operation of signals associated 15 with the line with which connection is made. Its several objects are to cause the act of making connection to a line in response to a call from a different line to determine the 20 transmission of a calling-current in the called line and to discontinue the calling-current when the called subscriber answers; to disconnect the operator's telephone from the plug-circuit when connection is made with 25 the line, the telephone having been normally in connection with the line for testing purposes; to associate with the line a supervisory signal responsive to currents in the line determined by the position of the telephone at 30 the substation, but to efface this signal during the transmission of calling-current, permitting its free operation only in a subsequent stage of the connection, and to associate the various agencies for accomplishing 35 these ends with the circuits and appliances of a certain well-known type of switchboard.

Prior to this invention various appliances have been constructed for automatically ringing the bell at a subscriber's station, the application 40 of the calling-current being determined by the act of making connection with the line and its cessation being caused automatically in the called subscriber's response to the call. Such appliances have commonly 45 involved mechanical means for determining the duration of current, together with mechanical catches and equivalent devices controlled by magnets for disconnecting the source of calling-current.

50 The present invention aims to eliminate all mechanical interlocking mechanism, deter-

mining the performance of all functions of the calling and telephone-controlling appliance through electrically-operated instrumentalities.

55

To this end it comprises an electromagnetic helix and means controlled in making connection with the line for exciting the helix, a switch actuated by the helix for applying current to the line, a second electromagnetic 60 helix controlled by current in the line determined by a change in the resistance of the line, and a switch actuated by this last-mentioned helix for disconnecting the source of calling-current. It further consists in the 65 combination, with the elements before mentioned, of a local circuit controlled by the said second helix adapted to maintain the excitation of the helix independently of current in the line.

70

It also contemplates the combination of the electromagnetic helix with the local circuits of the so-called "relay-switchboard," hereinafter to be described; circuits of the operator's telephone broken through the instrumentality 75 of the first-mentioned magnetic helix; means for bringing the supervisory signal into temporary association with the line, said means being controlled by the second-mentioned electromagnetic helix, and various other details of apparatus and circuits, which will be 80 fully set forth.

The type of switchboard hereinbefore referred to to which this invention is especially applicable comprises a relay for each line and 85 a secondary line-signal controlled thereby, a cut-off relay for each line adapted to sever the normal line connections with the relay, and a local circuit closed in making connection with the line to excite the cut-off relay, 90 a supervisory signal in the local circuit associated with the plug used in making connection with the line, and a relay responsive to currents in the line determined in the use of the telephone controlling the display of the 95 supervisory signal. In applying my invention in a switchboard of this type I construct the electromagnet for applying the calling-current to the line of comparatively high resistance and interpose it in the circuit with 100 the supervisory lamp and the cut-off relay. I make the magnet for disconnecting the call-

ing-current of low resistance and include it in a shunt-circuit of the supervisory lamp and the other magnet controlled by the supervisory relay responsive to currents in the telephone-line, and I furnish a local circuit closed through the agency of the last-mentioned electromagnet of the calling appliance to shunt the other electromagnet through itself. The telephone normally connected with the line is disconnected by switch-contacts controlled by the magnet which applies the calling-current, and a normal break in the plug-circuit for preventing the flow of calling-current over the calling-line is completed by the electromagnet, which cuts off the calling-current. Hence in the operation of this appliance the establishment of connection to a line cuts off the line-relay, applies calling-current to the line, and disconnects the operator's telephone therefrom, the supervisory signal being rendered inert through the resistance of the electromagnet in series with it, while the removal of the telephone for use at the called station disconnects the calling-current, closes the normal break in the plug-circuit, and brings the auxiliary supervisory signal under control of the supervisory relay by cutting out the resistance of the said magnet in circuit with the signal. After the response of the called party subsequent changes of line resistance are ineffective to break the plug-circuit, to cause the application of calling-current to the line, or to introduce resistance into the line-circuit of the supervisory signal. In addition to the above-mentioned appliances I provide a commutator for determining the intermittent application of calling-current to the line and for connecting a source of constant current not adapted for operating the substation-bell with the line in the intermissions of calling-current, so that the response of the called subscriber will instantly place the plug-circuit in condition to permit conversation.

This invention is especially useful in-connection with incoming trunk-lines in central offices, inasmuch as the operator making connection therewith is under no necessity of communicating with a subscriber or doing other work involving the prolonged use of her telephone in connection with the line, her sole duty being to test the line called for, to make connection with it, and to transmit a call-signal to the station. Hence the use of this automatic calling and telephone-controlling apparatus on incoming trunk-lines avoids the manipulation of all keys and similar appliances, reducing the acts required on the part of the operator to testing the line called for and inserting the plug into the spring-jack thereof when the line is free for connection.

The invention is illustrated in the attached drawings in association with a switchboard of the type hereinbefore mentioned.

Figure 1 of the drawings is a diagram representing the circuits and the elements of the

apparatus involved in a telephone-switchboard. This drawing shows the incoming terminal of a telephone trunk-line, together with the call-wire whereby the incoming trunk-operator commonly receives her orders from distant exchanges, a single telephone-line being shown terminating in the usual apparatus of the switchboard. Fig. 2 is an elevation of the appliance for controlling the connection with the trunk-line circuit of the source of calling-current and of the telephone and for determining the operation of the supervisory signal. Fig. 3 is a plan of the same device. Fig. 4 is an elevation of the opposite side. Figs. 5 and 6 are sectional views of the calling appliance on lines 55 and 66, respectively, of Fig. 2.

Referring to the diagram Fig. 1, conductors 1 and 2 are the wires of an incoming trunk-line from a different office of an exchange system. This trunk-line terminates, in effect, in a plug. This plug and the appliances associated with it, to be presently described, are located with others in an incoming trunk-line switchboard, as is well understood by those familiar with telephony. All subscribers' lines centering in the office which this trunk-line enters appear in spring-jacks in the incoming trunk-switchboard or are made accessible to the incoming trunk operator by any other suitable means. In the drawings the single substation-line shown is represented as provided with a spring-jack in the incoming trunk-switchboard and with another spring-jack and with suitable calling apparatus in a different switchboard in the same office.

The substation is furnished with suitable telephonic and calling apparatus, comprising a receiving-telephone *a*, a transmitting-telephone *a'*, a polarized call-bell *a''*, a condenser *a'''*, and a telephone-switch *a''''*. The call-bell and the condenser are connected in a permanently-closed bridge of the line-circuit, which is, however, open as respects continuous currents, while the telephones are located in a normally open bridge, which becomes closed when the telephone is removed from the telephone-switch. The line conductors 34 from this station are led from these appliances to a spring-jack *b* in the incoming trunk-switchboard and to a spring-jack *b'* in another switchboard, which may be one arranged for the establishment of local or office connections. Each line conductor is connected in multiple with a line-contact of each of these spring-jacks. Extensions of the line conductors are led to the poles of a battery *c* and to earth, respectively, the winding of a signal-controlling relay *d* being interposed in conductor 3. This relay is adapted to complete a local circuit 56, including a secondary line-signal *e*, together with a source of current. The signal *e* constitutes the subscriber's means of calling for a connection and may be associated with the spring-jack *b'* in the switchboard. The line conductors

3 and 4 also traverse the switch-contacts of the cut-off relay f , which is adapted to break the normal extensions of the line to earth and to battery when the magnet of the cut-off relay is excited. The magnet of this relay is connected in a grounded conductor 7, which leads to terminal contact-rings of all spring-jacks b and b' of the line. This circuit is designed to coöperate with another, presently to be described, which becomes completed when connection is made with the line, so that the normal earth connections of the line are broken during the use of the line for conversation.

15 The terminal plug g of the incoming trunk-line is adapted for insertion into the spring-jack b and comprises three contact-pieces g' , g^2 , and g^3 for registering with the two line-contacts and the local contact-ring of the jack. The line-contacts g' and g^2 form the terminals of the wires 1 and 2, respectively, of the trunk-line. A conductor 8 forms a permanently-closed bridge of the trunk-line. This conductor includes a source h of current for supplying the substation-transmitter of a line with which the trunk-line may be brought into connection and for operating signals associated with the trunk-line, together with impedance-coils, which serve to prevent the shunting of telephonic currents through the bridge. Conductor 2, leading to the contact-ring g^3 of the plug, includes the magnet-winding of a relay i for controlling a supervisory signal j , associated with plug g in the switchboard. The instrumentalites through which the relay i controls the display of signal j will be hereinafter described. Other circuit connections of the trunk-line also exist with an appliance which I shall designate the "calling appliance," although its function comprises not only that of signaling the called station, but of disconnecting the testing apparatus and of controlling a signal. This appliance is represented in Figs. 2, 3, and 4 and will now be described.

Two magnets k and l are provided, with their cores arranged coaxially. Each magnet is furnished with inwardly-bent pole-pieces k' k^2 and l' l^2 , respectively, the pole-pieces k^2 and l^2 being secured together. Each magnet is provided with an armature lying between the inwardly-extending ends of the pole-pieces and the spool of the magnet, fastened at one end to one of the pole-pieces and having its other end free and lying near the other pole-piece. Thus armature k^3 of magnet k is secured to pole-piece k' by a thin flat strip of metal k^4 , which may be a flexible ribbon of iron about one thousandth of an inch thick. The other extremity of armature k^3 lies facing the inner surface of the pole-piece k^2 , so that if the magnet be excited the armature will be drawn up into contact with the pole-piece, completing the magnetic circuit of the core. Similarly armature l^3 of magnet l is secured at one end to pole-piece l' and has its other extremity in

position to be attracted to pole-piece l^2 . The pole-piece l' carries four switch-springs m m' and n n' , these springs being rigidly secured between blocks of insulating material fastened to the pole-piece l' and extending parallel with the axis of the magnets. The free extremities of springs n and n' rest normally on studs n^2 n^3 , of insulating material, which project from the outer face of pole-piece l^2 . Spring m rests similarly on another stud m^2 , projecting from the pole-piece, while spring m' rests on a contact-anvil m^3 , secured to the pole-piece, but insulated therefrom. Spring n carries a contact-piece n^4 , which is adapted to impinge upon spring m when spring n is lifted. Beneath this contact-piece n^4 the armature l carries a projecting pin l^5 , of insulating material, which is thrust against the spring n to raise it and force it upward against spring m when the armature is raised. Near its other edge, beneath the spring n' , the armature l^3 carries a contact-stud l^6 , which is adapted to strike and make contact with spring n' when the armature is raised and to thrust the latter against an insulating-pin m^4 to lift spring m' from its resting-anvil. The pole-piece k' of magnet k likewise carries two switch-springs o and o' , insulated from it. The free extremities of these springs extend forward beneath the extremities of springs m and m' , respectively, and are adapted to strike and make contact with these springs, at the same time lifting them from their normal resting-places when the armature k^3 is attracted in the excitement of magnet k . These springs when at rest lie upon insulating-stops o^2 o^3 in the pole-piece k^2 .

Normally springs n and n' rest on their insulating-stops n^2 and n^3 , respectively, while springs m and m' rest on their stop m^2 and contact m^3 . Springs o and o' rest on their stops o^2 and o^3 out of contact with springs m and m' . When armature k^3 is raised through the excitement of its magnet, its contact-pieces are thrust against springs m and m' , respectively, raising spring m from its stop m^2 and spring m' from its anvil m^3 . When now armature l^3 is raised, the insulating-pin l^5 strikes the spring n , raising it from its stop n^2 and thrusting the contact n^4 against the spring m , thereby raising the latter spring away from the contact-spring o , while the contact-stud l^6 is thrust against spring n' , making electrical connection with it, forcing it against the stud m^4 , and thus raising the spring m' from the contact-spring o' .

The calling appliance is located in any suitable position in the switchboard. Spring m' of this appliance is connected by wire 9 with conductor 1. Conductor 2 of the trunk-line circuit is severed, the incoming end of the wire being connected with contact-spring n and the wire leading through the supervisory relay to the contact-piece g^3 of the plug being connected with the contact-spring m . Spring o' is connected with earth. Spring o is connected with a brush or contact-piece resting

- on a constantly-rotating commutator p , having two segments, one of which, p' , forms about one-fourth of the periphery, and the other of which, p^2 , forms nearly the remaining three-fourths. The segment p' constitutes one terminal of a generator p^3 of alternating calling-current, the other terminal of the generator being grounded. The segment p^2 forms one terminal of a grounded battery 10 of electromotive force substantially equal to that of battery h . The commutator may be arranged to rotate once in twelve seconds. Hence this device will apply the generator p^3 and the battery alternately to the spring o , 15 the duration of the connection of the calling-generator being three seconds and that of the source of steady current nine seconds in each period.
- The operator is provided with the usual 20 telephone q for testing purposes and for receiving orders over an order-wire 10. A branch 11 from this telephone, whose circuit is grounded, is led to the contact-anvil m^3 .
- The contact-piece g^3 of the plug forms the 25 terminal of a group of conductors leading from the free pole of a grounded battery r , which are involved in the operation of the cut-off relay, the supervisory signal, and the calling appliance. One terminal of magnet 30 k is connected by wire 12 with the free pole of battery r , and one terminal of magnet l is likewise connected by wire 13 with the same battery. The other terminal of magnet k is connected by wire 14 with signal-lamp j , from 35 which the circuit is led by wire 15 to contact g^3 of the plug. The other terminal of magnet l is connected by wire 16 with the armature i' of relay i and also by wire 17 with the armature l^3 of magnet l . Contact n' is connected 40 by wire 18 with wire 14 from magnet k . The contact-anvil i^2 of relay i is united by wire 19 with wire 15, leading to the contact-piece g^3 . The battery r may have an electromotive force of ten volts, then the cut-off relay f may 45 have a resistance of twenty ohms, the signal-lamp i should require two-tenths of an ampere at four volts electromotive force, and the magnet k should be of thirty ohms and magnet l of six ohms.
- The mode of calling the central office to obtain 50 a connection with the correspondent line will be readily apparent, but may be briefly traced. The removal of the telephone from its switch for use at the station permits current to flow from the battery c at the central office through the relay d over the line-wires, returning to the battery c at the central office. This relay being excited closes the local circuit 55 56, leading to the secondary line-signal 60 e , and thus signaling the call to the operator. It is assumed that the connection is to be made at a switchboard wherein the spring-jack b' is located. This act of answering the call will be made with a plug and plug-circuit 65 of well-known construction having local circuit connections with the battery r , which apply a current to conductor 7 for exciting

the cut-off relay and which involve suitable supervisory signals associated with the plug and plug-circuit. The excitement of the cut-off relay f breaks the normal extensions of the line conductors 3 and 4 to the battery h and to earth, respectively, and leaves the line connected with the plug-circuit. 70

Obviously the mechanism forming the subject of this invention concerns incoming calls, however, or connections to be made to the line to station A, whether by means of a plug-circuit terminating in a plug g and wholly located within the same office or by means of a 80 trunk-line circuit from a different office. It will be apparent that the conductors 1 and 2 might extend to an answering-plug at the switchboard whereon the spring-jack b' is located, in which case the insertion of plug g 85 into a spring-jack of a line to be called would signal the called party automatically, the functions of the calling appliance being exercised in the same way as in connection with a trunk-line; but inasmuch as an operator 90 engaged in answering calls is required to perform various special acts and to hold conversation with subscribers in the process of making connection the automatic ringing appliance is of greater advantage in connection with 95 incoming trunk-lines in the manipulation of which the incoming trunk operator is not called upon to perform any acts out of the regular routine of few motions. Hence the invention has been shown and will be described 100 in connection with incoming trunk-lines, although it will be understood that the contrivance is applicable to any calling-plug.

An operator at a distant office to which 105 trunk-line 1 2 extends having received a call for connection with the station A of the office herein described brings her transmitting-telephone into connection with order-wire 10 and, addressing the operator listening at telephone q , instructs her to make connection with line 110 to station A by means of trunk-line 1 2. Of course any of the well-known modes of selecting or designating the trunk-line to be used 115 may be employed. The operator taking the plug g applies the tip g' of the plug to the contact-ring of spring-jack b' of the line called for in the switchboard herein described. This act connects her grounded telephone q with the contact-ring through conductors 1 9 11, the contact-spring m' being at rest on its anvil m^3 . If the line were in use a battery r 120 would be connected with the contact-ring of some spring-jack, so that a current would flow through the telephone of the operator making the test at each application of the 125 testing-plug to the jack. Finding the line free for connection the operator inserts plug g into the spring-jack b' . This act brings the contact g^3 into registration with the contact-ring of spring-jack b' and completes a 130 local circuit of battery r as follows: from the free pole of the battery through wires 12, 14, 15, and 7, including the magnet k , lamp-signal j , and cut-off relay f . The cur-

rent in this circuit is insufficient to light the signal-lamp *j*, but is sufficient to excite the magnets *k* and *f*. The excitement of the cut-off relay *f* breaks the normal earth connections of the line. The magnetization of magnet *k* brings the springs *o* and *o'* into contact with the springs *m* and *m'*, respectively, at the same time breaking contact between the anvil *m³* and spring *m'*, whereby the operator's telephone is disconnected from the plug-circuit and the calling-current is applied to it. Conductor 1 of the plug-circuit is grounded and conductor 2 is brought into connection with the commutator *p* through the agency of spring *o*. In the rotation of the commutator the battery and the generator are alternately applied to the conductor 2. Obviously each application of the generator *p³* will ring the substation-bell *a²*. The current from this generator, being greatly impeded by the condenser and the bell *a²* at the substation, will be insufficient to excite the relay *i*. When the telephone at the station is removed from its switch in response to the call, a path of low resistance is created at the substation. Current will flow from either the battery or the generator *p³* through the low-resistance path thus produced sufficient in quantity to excite the relay *i* and cause it to attract its armature *i'*. The purpose of applying the battery to the line in the intervals of the application of calling-current is twofold: first, that the disconnection of the calling apparatus and the completion of the plug-circuit may instantly follow the taking of the telephone at the substation, whatever be the position of commutator *p*, and, second, that the excitement of relay *i* may be insured by the passage of a steady current rather than to be dependent on current of alternating character, such as the calling-current. The attraction of armature *i'* into contact with its anvil *i²* closes a branch of the local circuit through wires 13, 16, and 19, including the magnet *l*. This magnet being excited thrusts the contact *n* against the contact-spring *m* and raises contact-springs *m* and *m'* from the springs *o* and *o'*, at the same time closing contact between armature *l³* and contact-spring *n'*. The conductor 2 of the plug-circuit is thus completed, the source of calling-current is disconnected from the circuit, and the local circuits are shifted as follows: Circuit is closed through wires 13, 16, 17, and 18 in shunt of magnet *k* and including the magnet *l*. Inasmuch as this circuit is independent of the contacts *i'* and *i²*, the magnet *l* is no longer controlled by the supervisory relay *i*, and will remain excited as long as the local circuit 12, 13, 16, 17, 18, 14, 15, 7 remains closed—that is, while the connection remains. The resistance in circuit with the lamp *j* is greatly reduced through the shunting of magnet *k* by magnet *l*, so that the current through the signal-lamp may be sufficient to light the lamp. It will be noted, however, that this lamp is now subject to the control of su-

pervisory relay *i*, inasmuch as the supervisory relay closes a shunt-circuit 19 16 about the lamp when it is excited. While the calling appliance was in operation the signal-lamp *j* remained dark on account of the high resistance in its circuit. Thus confusion of the operator by meaningless signals is avoided. After the response of the called party and the disconnection of the calling-current the supervisory signal becomes effective and is controlled by the relay *i* in response to the operation of the telephone-switch at the substation in the usual way. When at the termination of conversation the telephone is replaced on its switch, the relay *i* is deprived of current, the shunt about the signal-lamp is broken, and the lamp becomes lighted. Its illumination may serve as a signal for disconnection, to be followed by the withdrawal of plug *g* from spring-jack *b'*. When the plug is thus withdrawn, the magnets *l* and *k* are deprived of current and the calling appliance is returned to its normal condition.

My invention is defined in the following claims:

1. The combination with a telephone-line extending from a substation to a central office, and a switch at the substation of the line for determining the flow of current therein, a magnet responsive to current in the line, a source of calling-current and means for applying the same to the line, an electromagnetic switch controlled through the agency of the switch at the substation, for disconnecting the source of calling-current from the line, a supervisory signal adapted to be controlled by the first-mentioned magnet, circuit connections rendering the signal unresponsive to said magnet, and means controlled by said electromagnetic switch for changing said circuit connections and bringing the supervisory signal under the control of said magnet, substantially as set forth. 95

2. The combination with a telephone-line extending from a substation to a central office, and a switch at the substation, actuated in the use of the telephone, for determining the flow of current in the line, a source of calling-current and means for applying the same to the line, a source of direct current, an electromagnetic switch adapted to disconnect the said source of calling-current and connect the source of direct current, a relay responsive to current in the line, and a local circuit controlled by said relay including said electromagnetic switch, whereby said electromagnetic switch is operated when the substation-telephone is brought into use, as set forth. 115

3. The combination with a telephone-line extending from a substation to a central office, a switch at the substation, actuated in the use of the telephone, for controlling the circuit of the line, means at the central office for making connection with the line, a source of current, a relay responsive to the flow of current in the line, a source of calling-current 130

- and an electromagnetic switch adapted to connect said source of calling-current with the line, a local circuit closed in making connection with the line to operate said electromagnetic switch, a second electromagnetic switch adapted to disconnect the calling-current from the line, a local circuit controlled by said relay for operating said last-mentioned switch, a supervisory signal adapted to be controlled by said relay, circuit connections normally rendering said signal unresponsive to the relay, and means, controlled by the last-mentioned switch, for bringing said supervisory signal under the control of the relay, substantially as described.
4. The combination with a telephone-line, a line-signal therefor in normal circuit connection with the line, spring-jacks for making connection with the line, and a cut-off relay for severing the normal circuit to the signal in a portion of a local circuit terminating in contact-pieces of said spring-jacks adapted to register with contact-pieces of a plug inserted in a jack, a source of calling-current, an electromagnetic switch for applying said source of calling-current to the plug-circuit, said electromagnetic switch being in a conductor terminating in said local contact-piece of the plug, and suitable means for disconnecting the source of calling-current; whereby the calling-current is applied and the line-signals are disconnected from the line when the plug is inserted in a spring-jack of the line, as described.
5. The combination with a telephone-line having normal connections with a line-signal, means for making connection with the line comprising spring-jacks of the line and a plug and plug-circuit, a cut-off relay for severing the normal earth connections of the line and a local contact including the said cut-off relay comprising a conductor associated with the line including the magnet of the relay and a part terminating in a local contact-piece of the plug, a supervisory signal-lamp in the conductor terminating in said local contact-piece of the plug, a source of calling-current, an electromagnetic switch for applying the source of current to the telephone-line, circuit connections of the magnet of said switch with the local circuit adapted to prevent the lighting of the lamp, a supervisory relay for controlling the lamp, means for eliminating the magnet of the electromagnetic switch from the local circuit of the lamp, as described; whereby the signal-lamp is rendered ineffective during the transmission of calling-current by the electromagnetic switch in its circuit.
6. The combination with a telephone-line, a switch at the station for changing the resistance of the line in the use of the telephone, a supervisory signal associated with the line, a relay responsive to current in the line controlling said signal, a source of calling-current and a switch for applying the said source of current to the line to call, circuit

connections of the signal adapted to render it inert, and switch-contacts associated with the said appliance for connecting calling-current with the line controlling the circuit connections, whereby the signal-lamp is rendered ineffective during the transmission of a call, as described.

7. The combination with a telephone-line and a switch for changing the resistance of the line in response to a call, a source of calling-current and means for applying it to the line, a supervisory signal normally responsive to currents in the line, an electromagnetic switch adapted to disconnect the source of calling-current from the line, said switch being responsive to change of current in the line produced in the use of the telephone, circuit connections of the supervisory signal adapted to interrupt the control of said signal by currents in the line, and an appliance associated with the said electromagnetic switch controlling the circuit connections, whereby the signal is rendered ineffective during the sending of a call but is automatically rendered effective when the call receives response, as described.

8. The combination with a telephone-line, a supervisory relay in the line responsive to currents therein determined in the use of the telephone, a supervisory lamp-signal normally controlled thereby in a local circuit closed in making connection with the line, a source of calling-current and an electromagnetic switch adapted to apply said calling-current to the line, the magnet of said switch being of high resistance and being located in series with the lamp-signal, an electromagnet responsive to current in the line and a switch controlled thereby adapted to shunt the electromagnet of said electromagnetic switch, as described.

9. The combination with a telephone-line having a switch at its substation for determining the flow of current in the line in the use of the telephone, a relay responsive to currents in the line, a local circuit associated with the line divided at one point into parallel branches, completed in switch-contacts closed in making connection with the line, a source of calling-current, an electromagnetic switch adapted to apply said source of calling-current to the line, said switch having its electromagnet in one branch of the said local circuit, a second electromagnetic switch adapted to break the connections of the said source of calling-current with the line, said switch being in the other of the parallel branches, said second-mentioned branch being controlled by the relay responsive to currents in the line, as described.

10. The combination with a telephone-line and a switch at the station thereof for determining the flow of current in the line in the use of the telephone, of a local circuit associated with the line in a switchboard, and switch-contacts closed together in the act of making connection with the line to complete

the said circuit, said circuit being divided into parallel branches, of a source of calling-current, an electromagnetic switch adapted to apply the said source of current to the line, the magnet of said switch being in one of said branches, a second electromagnetic switch adapted to break the connection of said source of current with the line, said electromagnetic switch being in the other of said branches, a supervisory signal in the first-mentioned branch, a relay responsive to currents in the line having its switch-contacts in the second-mentioned branch, and a switch actuated by the magnet in said second-mentioned branch adapted to shunt the magnet of the switch in said first-mentioned branch, as described.

11. The combination with a telephone-line and a switch at the station thereof for determining the flow of current in the line in the use of the telephone, of a local circuit associated with the line in a switchboard, and switch-contacts closed together in the act of making connection with the line to complete the said circuit, said circuit being divided into parallel branches, of a source of calling-current, an electromagnetic switch adapted to apply the said source of current to the line, the magnet of said switch being in one of said branches, a second electromagnetic switch adapted to break the connection of said source of current with the line, said electromagnetic switch being in the other of said branches, a supervisory signal in the first-mentioned branch, a relay responsive to currents in the line having its switch-contacts in the second-mentioned branch, and a switch actuated by the magnet in said second-mentioned branch adapted to bring the magnet in said second-mentioned branch into parallel with a magnet in said first-mentioned branch, the magnet in said second-mentioned branch being of low resistance, substantially as described.

12. The combination with a telephone-line extending from a substation to a central office, and a switch at the substation, actuated in the use of the telephone, for changing the resistance of the line-circuit, of a source of calling-current and means for breaking the telephone-line circuit and connecting said source of calling-current with the end leading to the substation, a magnet in the line-circuit traversed by calling-current, said magnet being responsive to increased current in the circuit, a switch operated by said magnet for disconnecting said source of calling-current and simultaneously completing the telephone-line circuit, a source of steady current, and a continuously - rotating commutator adapted to complete the circuit of said source of calling-current intermittently and to substitute therefor said source of steady current in the intermissions, whereby a source of current is always included in circuit with said magnet to excite the same when the called party responds, substantially as described.

13. The combination with a telephone-line having normal connections between its line

conductors, a cut-off relay controlling the said normal connections, spring-jacks of the line and a local circuit terminating in local contact-pieces of the jacks including the magnet of said cut-off relay, a plug and plug-circuit for making connection with the line, and a conductor adapted to coöperate with the said local conductor associated with the line terminating in a contact-piece of the plug adapted to register with a contact-piece of the spring-jack in which the plug is inserted, said local circuit associated with the plug being divided into parallel branches; a relay in the plug-circuit responsive to currents in the line determined in the use of the telephone, said relay controlling one of said branches, and a supervisory lamp-signal in the other branch; a source of calling-current, an electromagnetic switch for connecting the terminals of said source of current with the plug-circuit, the electromagnet of said switch being included in the branch of the local circuit with the signal-lamp; an electromagnetic switch adapted to break the connection of said source of calling-current with the line, the electromagnet of said switch being included in the branch of the local circuit controlled by the supervisory relay, and local circuit connections controlled by said second-mentioned electromagnetic switch adapted to bring the magnet thereof into shunt of the magnet of said first-mentioned switch, said magnet being of low resistance, substantially as described.

14. In combination with a plug and plug-circuit a pair of switch-springs connected with the different conductors of the plug-circuit, a resting-anvil for one of said springs forming the terminal of an operator's telephone for testing, switch-springs adapted to be thrust against the said springs to make contact with them and to raise one of the springs from the said contact-anvil, an electromagnet controlling said second-mentioned pair of springs, said magnet being in a local circuit closed in the use of the plug as described; whereby calling-current is applied and the plug-circuit of the operator's telephone is disconnected in using the plug, as described.

15. In a calling appliance for a plug-circuit the combination of two pairs of springs adapted to form electrical contact with each other, one of said pairs of springs being connected with the plug-circuit and the other with the terminals of a source of calling-current, of two electromagnets, one acting upon the terminal springs of said source of current to thrust them against the other springs, and the other magnet adapted to act on said springs connected with the plug-circuit to raise them from the other springs, and means for exciting the magnet for applying the calling-current and the magnet for disconnecting the calling-current successively, as described.

16. The combination in a calling appliance

for association with the plug-circuit, of three springs normally out of contact with each other, two of said springs forming normally-separated terminals of a plug in the plug-circuit, and the other spring forming the terminal of a source of calling-current, two magnets, one adapted to thrust said calling-spring against one of said plug-circuit springs, and the other magnet adapted to thrust one of said plug-circuit springs against the other, raising the latter from the calling-springs, and means for exciting the said magnets successively in the order of their description.

17. The combination in a calling appliance for association with the plug-circuit, of a pair of switch-springs connected with the terminal plug, a switch-spring beneath one of these connected with the plug-circuit but disconnected from the terminal plug, a pair of switch-springs forming the terminals of a source of calling-current, an electromagnet adapted to thrust said calling-springs into contact with said springs connected with the plug-circuit, of an electromagnet adapted to thrust the springs connected with the like conductors of the plug-circuit into contact with each other, and simultaneously to raise the springs connected with the plug-circuit from the calling-springs, and means for exciting the magnets successively in the order described.

18. In a calling appliance, the combination with switch-springs m and n forming terminals of a break in one side of a plug-circuit, a switch-spring m' connected with the other side of the plug-circuit, calling-springs o and o' , switch-spring n' and contact l^6 therefor, a normal resting-anvil m^3 for the spring m' , of the magnet k for thrusting springs o and o' into contact with springs m and m' , a magnet l for thrusting spring n into contact with spring m , raising springs m and m' from springs o and o' and closing contacts $l^6 n'$, means for exciting the magnets successively, and a local circuit controlled in contacts $l^6 n'$ including the magnet l , as described.

19. The combination with a magnet and pole-pieces thereof projecting toward each other, and an armature lying between the magnet and the pole-pieces, of the switch-springs n and m adapted to be raised and pressed into contact when the armature is attracted, and a resting contact for the spring m , as described.

20. The combination with a plug and the plug-circuit thereof, of a testing appliance in normal connection with the plug-circuit, a source of calling-current, an electromagnetic switch adapted to break the connection of said testing appliance and to make connection of said source of calling-current with the plug-circuit, and local circuit connections of the said switch made operative in using the plug to excite the switch, an electromagnet adapted to break the circuit of the source of calling-current, and means controlled from the called station for operating said last-mentioned magnet, as described.

21. The combination with a trunk-line and the terminal plug thereof, a subscriber's line and a spring-jack therefor, of an operator's telephone connected with the trunk-line, a source of calling-current, an electromagnetic switch adapted to break the circuit of the telephone and apply the source of calling-current to the line, and circuits made operative in registering contacts of the plug and jack to excite the magnet of said switch, an electromagnetic switch adapted to break the circuit of the source of calling-current, and means actuated by increased current in the line for operating said switch, as described.

22. The combination with a telephone-line and means for changing the resistance of the line in the use of the telephone, a spring-jack for the line, a plug and plug-circuit for making connection with the spring-jack, a source of current and an electromagnetic switch for connecting the source of current with the plug-circuit, and circuit connections for exciting the actuating-magnet of said switch closed in registering contacts of the plug and spring-jack, an electromagnet in the path of current in the line, and a shunt of the actuating-magnet of said electromagnetic switch controlled by said last-mentioned magnet, whereby the source of calling-current is applied to the line when connection is made with the line, but is disconnected therefrom in the use of the telephone, as described.

In witness whereof I hereunto subscribe my name this 28th day of April, A. D. 1898.

FRANK R. MCBERTY.
